UNITED STATES PATENT OFFICE.

FRED S. ENGLISH, OF NEW LONDON, CONNECTICUT.

FOLDING FEED TABLE FOR PRESSES.

Application filed September 2, 1926. Serial No. 133,216.

My invention relates to feed tables such as are used for a stack of sheets which are being fed to a printing press, a cutting and creasing press, or any other machine adapted 5 to operate on sheets; and I have chosen to illustrate my invention in connection with a well known type of printing press. The object of the invention is to provide a table for holding the sheets in position for the 10 feeder to take the sheets from, in feeding them to the press, and to provide a device of this character which may be folded up out of the way to permit ready access to the working parts of the press whenever this access is desired. In the complete embodiment of my invention I have shown the rear portion of the feed table arranged to be swung out of position to provide access to such parts of the press as the bed, and I have also shown the 15 forward portion of the feed board arranged to be swung and folded out of position to give access to the cylinder of the press. My invention also includes a device having these characteristics and which is simple in construction and operation, and which may be operated quickly. With these and other objects in view my invention consists of the features hereinafter described in detail.

In the drawings forming part of the application,

Figure 1 is an elevation of a portion of a press showing my invention applied thereto,

Figure 2 is a plan view of one side of the device shown in Figure 1,

Figure 3 is a detail sectional view on an enlarged scale showing the tracks for guiding one section of the table in conjunction with another,

Figure 4 is a view corresponding with Figure 1, showing the rear portion of the feed table elevated to give access to the bed of the press,

Figure 5 is a similar view of the same device elevated to provide access to the cylinder of the press,

Figure 6 is a view at one end of the press showing my invention in a modified form, and

Figure 7 is a similar view of my invention in a slightly modified form.

Referring first to the construction shown in Figures 1, 2 and 3 the cylinder of the press is indicated by the numeral 1, 2 is a portion of the side frame of the press, and 3 is a feed table bracket which is mounted on the side frame and forms the principal support for the feed table; 4 is a small bracket bolted on

the side frame of the press and it serves to support the front leaf of the feed table adjacent the cylinder 1. It will be understood that the members associated with the feed table are duplicated at opposite sides of the press and a description of parts of one side will therefore serve as a description of both sides. There is a stud 5 which is mounted on the upper end of the bracket 3 and it extends inwardly or toward the center line of the press as shown in Figure 2. This stud and a companion stud at the opposite side of the press form a pivot for the parts which carry the feed table.

The forward portion of the feed table is shown composed of comparatively narrow leaves 6 and 7 and the rear section is composed of a leaf 9. Between the leaves 7 and 9 I have shown an intermediate leaf 14. This leaf is connected with the leaf 9 my means of hinges 15 which permit these leaves to pivot in relation to each other. The leaves 6 and 7 are attached to the lever arms 8, these arms pivoting from the studs 5. The rear leaf is attached to the arms 16 and they pivot upon the studs 5. The arm 16, which will be duplicated at the opposite side of the press, has a projection 17 directed at an angle to the plane of the lever arm 16 in such relation that this extension will come up against the stop pin 18 which is attached to the table bracket 3 when the table is folded into the position shown in Figure 4.

It will be observed in Figure 1 that there is a gap 19 between the leaves 7 and 14 which is relatively narrower at the top surfaces of these leaves but this gap broadens out near the under sides of the leaves as is indicated by the line 20 (Figure 3) on which the leaf 14 is chamfered. At each side of the leaf 14 there is attached a metal shoe or runner 21 which extends downwardly adjacent the front edge of the leaf 14 to the plane of the bottom of this leaf and then it extends rearwardly along the leaf at the side edge of it. There is a similar shoe or runner 22 arranged at each side edge of the leaf 7 and this runner extends along the plane of the upper surface of this leaf and then turns downwardly at 22^a and projects to the plane of the lower surface of this leaf. There is a runner 23 attached at each side edge of the leaf 6 and this forms substantially a continuation of the runner 22.

The operation of this form of my invention is as follows: If it is desired to raise the rear

section of the feed table to permit access to the bed of the press or to the form 2^a the section 9 of the feed table with its supporting levers 16 is swung on the studs 5 to the position shown in Figure 4, whereupon the extensions 17 will rest against the pins 18 and support the parts in the position shown in this view. While the leaf 9 and its supports are being elevated to this position, this leaf 9 will 10 swing in relation to the leaf 14, because the leaf 9 is fixed to the lever arms 16, whereas the leaf 14 is only connected with these levers by reason of its hinge connection 15 with the leaf 9. When the lever arms 16 start to swing 15 upwardly the leaf 14 is forced forwardly in relation to the leaves 6 and 7, since there is nothing at this time tending to move the latter leaves, and the guides 21 on the leaf 14 will rise upwardly on the forward ends 22^a of the members 22 and on continued movement of the arms 16 the under portions of the shoes 21 will travel along the top portions of the members 22, and after traversing these members 22 the guides 21 will pass over onto 25 the members 23 of the leaf 6. During this movement of the leaf 14 the latter is kept from touching the leaves 7 and 6 by reason of the long bevel or chamfered edge 20 which permits the guiding members 21, 22 and 23 to 30 slide in relation to each other without having the leaves come into direct contact. When the feed table is moved to the position shown in Figure 4 the operator has a wide space in which to operate upon the form carried upon 35 the bed of the press, the dotted line 24, 25 indicating the limit of access to the form.

When it is desired to approach the cylinder 1 in this form of the invention the table leaf 9 will remain in its lower position, as shown in Figure 5 and the lever arms 16 will lie in substantially the horizontal position. The arms 8, however, together with the leaves 6 and 7, will be swung upwardly upon the studs 5 until the parts arrive at the position shown 45 in Figure 5 when the extensions 8^a of the arms 8 will strike the stop pins 11 and support the parts in this position. While the parts are being moved to this position, the folding action of the leaves will take place in the same 50 manner as first described. That is to say, as the arms 8 swing upwardly they carry the table leaves 6 and 7 and cause the leaf 14 to pivot on the hinges 15 in relation to the leaf 9 which latter is now stationary. At the first 55 part of this movement the members 21 and the leaf 14 ride up the incline 22^a and thence along the tops of the guides 22 and 23. When the parts are elevated to the position shown in Figure 5 the operator will have free access to 60 the cylinder 1, limited only by the parts indicated by the line 26, 27. In this form of the invention there is free access to both the bed and the cylinder. And in this form of the invention the operation of the table so far as 65 the folding of the leaves is concerned, is au-

tomatic. That is to say, whether the lever arms 16 or the lever arms 8 are raised, the leaves automatically fold in relation to each other without special attention.

In Figure 6 I have shown the invention in a modified form. In this construction the rear leaf 30 of the feed table is mounted on the arms 16 which operate similar to the corresponding arms in Figures 4 and 5 and this leaf is provided with guides or tracks 31 at 70 the side edges which extend downwardly at 32 to the plane of the bottom of the leaf 30. The forward section of the table comprises a fixed leaf 33 attached to the lever arms 8 and the second leaf 34 which is connected to the first one by means of hinges 35 so that the latter leaf may swing in relation to the former one. The leaf 34 has guides or tracks 36 at the sides extending along the plane of the lower side of the leaf and turning thence upwardly at 37 to the plane of the top of the leaf. In this construction, when the arms 16 are swung upwardly, as shown in Figure 6, the member 36 will ride up the incline 32 and thence along the members 31 so that the leaf 34 is raised into the position shown in this figure. When the front section of the table is to be raised, the arms 16 and the leaf 30 remain down in substantially a horizontal position, and the arms 8 are raised. In this operation the leaf 34 will be forced to rise with its guide members 36, sliding over the guide members 31, the same as before. In this operation I prefer to chamfer the edge 38 of one of the leaves the same as shown in Figure 6 in order to prevent the leaves from striking one another and to confine the sliding action to the guiding members.

In Figure 7 I have shown a further modification. In this view there is a stationary leaf 39 attached to the lever arms 16 and there is a narrow leaf 40 connected by hinges 41 to the fixed leaf, so that it may lie in the same plane with the latter or be swung on the hinges 41 to overlap the leaf 39. There is a fixed leaf 42 attached to the lever arms 8 and at the rear there is a narrow leaf 43 attached to the fixed leaf 42 by hinges 44. This construction permits greater access to the bed of the press than in the former construction but it is necessary to fold the leaves 40, 43 by hand while raising either the lever arms 16 or the lever arms 8.

In each form of the invention I have shown a feed table the leaves of which are adapted to be folded up out of operative position, to provide ready access to the bed of the press, or the cylinder, and the folding operation may be performed very quickly.

Having described my invention, what I claim is:

1. In a press, a feed table for the stock, comprising front and rear sections mounted on supports to permit said sections to be swung into and out of active position, at least

- one of said sections including table leaves arranged to fold in relation to each other, for the purpose set forth.
2. In a press, a feed table for the stock, comprising front and rear sections adapted to lie in contiguous relation and mounted on supports which permit said sections to be swung into and out of active position, at least one of said sections including table leaves arranged to fold in relation to each other for the purpose set forth.
3. In a press, a feed table for the stock, comprising front and rear sections adapted to lie in contiguous relation and mounted on independent rocking supports, which permit said sections to be swung into and out of active position, at least one of said sections including leaves arranged to fold in relation to each other.
4. In a press, a feed table for the stock, comprising front and rear sections adapted to lie in contiguous relation and mounted on independent rocking supports having a common axis, said supports permitting said sections to be swung into and out of active position, at least one of said sections including leaves arranged to fold in relation to each other.
5. In a press, a feed table for the stock, comprising front and rear sections mounted on pivotal supports to permit said sections to be swung into and out of active position, one of said sections having a leaf adapted to be automatically rocked in relation to its support when said support is rocked.

6. In a press, a feed table for the stock, comprising front and rear sections mounted on pivotal supports to permit said sections to be swung into and out of active position, one of said sections having a leaf pivoted in relation to its support and engaging the other section of said table whereby said leaf will be swung on its support as its support is swung.

7. In a press, a feed table for the stock, comprising a plurality of contiguous sections each mounted on pivotal supports to be swung into and out of active position, one of said sections having a leaf pivoted in relation to its support, said latter leaf and the other of said sections having co-operating guiding means for causing said pivoted leaf to fold when swung with its supports.

8. In a press, a feed table for the stock, comprising a plurality of sections each mounted on pivotal supports to be swung into and out of active position, said sections comprising contiguous leaves the adjacent edges of which are spaced by an opening which widens toward the bottom of the leaves, one of said sections having a leaf pivoted in relation to its supports, said latter leaf and the other of said sections having co-operating guiding means for causing said pivoted leaf to fold.

Signed at the city and county of New London, State of Connecticut, this 25th day of August, 1926.

FRED S. ENGLISH.
